UNITED STATES PATENT OFFICE.

WILLIAM LIVINGSTON, OF NEW YORK, N. Y., ASSIGNOR TO THE NOESTING PIN TICKET COMPANY, INC., A CORPORATION OF NEW YORK.

PIN-TICKET.

1,224,183.

Specification of Letters Patent.

Patented May 1, 1917.

Application filed July 29, 1913. Serial No. 781,727.

To all whom it may concern:

Be it known that I, WILLIAM LIVINGSTON, a citizen of the United States, and a resident of the city, county, and State of New York, 5 have invented new and useful Improvements in Pin-Tickets, of which the following is a specification.

My invention relates to pin-tickets, particularly to that type of pin ticket having 10 a wire bent upon itself to form a double-shank pin with round point.

My invention is particularly addressed to the forming of a pin-ticket having two pins made of the same piece of wire, each of the 15 pins having a round point and a double shank and the means for holding said pins in engagement with the ticket.

In the drawing, forming a part hereof,

Figure 1 is a perspective view of the wire 20 forming the pins, showing the form it is in when in engagement with the ticket;

Fig. 2 shows the upper side of the ticket with the pins attached thereto; and

Fig. 3 shows the underside of the ticket 25 with the pins attached thereto.

In the drawing, A—A represents the double-shank pins formed of a piece of wire bent upon itself at two points to form the two pins with round ends, the shank A of 30 the pin being formed of two pieces of wire lying close to each other, as shown. At a predetermined point that portion of the wire connecting the two pins is bent to form the member B adapted to lie on one side 35 of the ticket, as shown in Fig. 2, and then folded over on the edge so as to form the member C to lie on the underside of the ticket, as shown in Fig. 3, said member C being connected by a member D on the 40 underside of the ticket. The shank of the pins passes through the ticket and the free ends are bent so as to form the members

E—E lying on the upper side of the ticket, and the members F—F lying on the under-side of the ticket, the extreme ends of the 45 wire passing through the ticket so as to permit the members F—F to lie on the under-side.

In the tickets formed in this way two pins are provided, with rounded points, made of 50 one piece of wire, which are rigidly held in engagement with the ticket.

Having described my invention what I claim is:—

1. A pin-ticket having a plurality of 55 round-pointed double-shank pins formed of a single piece of wire, the wire between said pins being bent so as to engage with the upper and under sides of said ticket, the free ends of said wire extending along one surface of said ticket and in engagement therewith and passing through openings in the ticket and engaging with the other surface of the ticket.

2. A pin-ticket having a plurality of 65 round-pointed double-shank pins formed of a single piece of wire, the wire between said pins being bent so as to engage with the upper and under sides of said ticket, the free ends of said wire extending 70 along one surface of said ticket and passing through openings in the ticket and engaging with the other surface thereof and so arranged that portions of the free ends are substantially parallel to a line extending 75 from one of said pins to another.

In testimony whereof, I have signed my name to this specification, in the presence of two subscribing witnesses.

WILLIAM LIVINGSTON.
